UNITED STATES PATENT OFFICE

IRVING H. REYNOLDS, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE

CONDENSER.

Application filed September 21, 1929. Serial No. 394,170.

The present invention relates in general to improvements in the art of heat transfer, and relates more specifically to improvements in the construction and operation of steam condensers of the type generally known as surface condensers. 5

An object of the invention is to provide an improved method of distributing the steam throughout the heat transferring area of a condenser.

10 Cpending application Serial No. 107,908, filed May 10, 1926 discloses instrumentalities for securing the desired distribution of steam throughout the tube area of a surface condenser with the aid of adjustable deflector plates or dampers located in passages or lanes formed between groups of the heat transferring tubes. While these adjustable dampers effectively accomplish their purpose as far as distribution of the steam is 15 concerned in a condenser wherein the steam is admitted to the inlet opening in a relatively uniform manner, they do not take care of distribution of the steam longitudinally of the tubes.

20 It is a more specific object of the present invention to provide improvements in distributing mechanisms such as disclosed in the said application, whereby relatively uniform and highly effective distribution of the steam throughout the length of the tubes may be effected, as well as laterally throughout the banks or groups of tubes. With the aid of the present invention, the distribution of the steam throughout the heat transferring area may be made uniform regardless of the fact that the distribution of steam at the inlet opening of the condenser may not be uniform. Such lack of uniformity in admission often results in cases 25 where the steam is delivered from a vertical or horizontal engine such as a turbine, to a condenser wherein the steam passes from the inlet toward the discharge at an angle to the direction of flow in the engine. The major portion of the steam tends to follow the direction of its course through the turbine, thereby causing greater quantities of steam to enter the spaces between 30 the condenser tubes at a point remote from

the discharge end of the turbine, than directly at such end.

Some of the novel features of steam distributing mechanism disclosed but not specifically claimed herein, form the subject matter of claims in the copending application hereinabove referred to. 55

A clear conception of several embodiments of the present improvement and of the mode of constructing and manipulating devices in accordance therewith, may be had by referring to the drawing accompanying and forming a part of this specification in which like reference characters designate the same or similar parts in the several views. 60

Fig. 1 is a relatively diagrammatic central longitudinal section through a surface condenser having the improvement applied therein. 65

Fig. 2 is a relatively diagrammatic transverse vertical section through the condenser shown in Fig. 1. 70

Fig. 3 is a relatively diagrammatic transverse vertical section through a surface condenser having another form of the invention applied therein. 75

Fig. 4 is an enlarged end view of the mechanism for distributing the steam throughout the condenser.

Referring specifically to Fig. 1, the improved surface condenser illustrated therein, comprises in general a main shell or casing 2 sometimes formed elliptical in cross-section, and having a plurality of parallel heat transferring tubes 3 extending throughout the length thereof. The tubes 3 are ordinarily supplied with cooling water from an inlet head 6 and the water is delivered from the tubes 3 through a discharge head 7. The casing 2 is provided with an inlet opening 4 through which the exhaust steam from the engine is delivered to the tubes 3, and the water of condensation which accumulates in the space 19 at the lower end of the casing 2 is discharged to a hot well through a connection 5 disposed at the lowermost portion of the condenser shell. The space within the casing 2 is divided into segregated compartments 16, 17, 18, by means of vertical partitions 11, 12 through which the 80

tubes 3 extend. These partitions 11, 12 may be disposed at any desired position along the tubes, depending upon the conditions under which the steam is admitted to the condenser shell, and may if desired be disposed other than at right angles to the tube axes, as shown.

The heat transferring tubes 3 are arranged in groups which are separated within each of the compartments 16, 17, 18, by means of 10 relatively large unobstructed passages or lanes 13, 14, 15. As illustrated in Figs. 1 and 2, the vertical lane 13 intersects the horizontal lanes 14, 15 at about the center of 15 the shell 2. Located directly adjacent to the junction between the lanes 13, 14, 15, and within each of the compartments 16, 17, 18, is a set of flow controlling plates or 20 dampers 8 which are adjustable to either divert the steam entering the central lane 13 laterally to the horizontal lanes 14, 15, or to permit direct passage of some or all of this steam downwardly and laterally away from the lane 13 to the groups of tubes located below the horizontal lanes 14, 15. The 25 dampers 8 in each compartment 16, 17, 18 extend throughout the length of the compartment, and are mounted to swing about pivots 23 which are supported by means of 30 fixed brackets 22. One damper 8 of each set is provided with an actuating arm 24 having a pin 25 which cooperates with a slot 26 formed in the end of a similar arm 24 secured to the other damper 8 of each set. 35 An actuating or adjusting rod 9 cooperates with one damper 8 of each set, and extends laterally through the wall of the casing 2, being provided at its outer extremity with suitable actuating means such as an adjusting hand wheel 10. By turning the hand wheel 10 from the exterior of the shell 2, the dampers 8 may be adjusted from vertical as shown in Fig. 2 to inclined position as shown in Fig. 4, or to any intermediate 40 position so as to direct either all or any portion of the steam entering the central lane 13 throughout the heat transferring space of each compartment 16, 17, 18.

In the embodiment of the invention illustrated in Fig. 3, the groups of tubes 3 are separated by several vertical lanes 20 and a horizontal lane 21. Sets of adjustable dampers 8 are disposed within the upper ends of each of the vertical lanes 20, and 50 similar sets of dampers may also be disposed at the intersections of the vertical and horizontal lanes, or at any other point, if so desired. In this embodiment it will be apparent that the steam entering the inlet opening 4 may be effectively distributed in any desired manner, throughout the groups of tubes 3 by controlling the admission of more or less steam to the lanes 20, 21.

When utilizing the invention, the dampers

8 may be adjusted so as to most effectively distribute the entering steam throughout the heat transferring area of the tubes 3. The dampers 8 of each compartment 16, 17, 18 may be independently adjusted so as to insure uniform distribution of the steam throughout the lengths of the tubes 3, by merely manipulating one or more of the adjusting mechanisms or hand wheels 10. Sets of the adjustable dampers 8 may obviously be located at any desired position throughout the condenser, and any number of steam distributing lanes may obviously be provided. It will thus be noted that the invention provides means for effectively preventing the passage of uncondensed steam to the hot well, thus insuring maximum efficiency in operation of the condenser.

It should be understood that it is not desired to limit the invention to the exact details of construction and operation herein shown and described, for various modifications within the scope of the appended claims may occur to persons skilled in the art.

It is claimed and desired to secure by Letters Patent:

1. In combination, a casing, means dividing said casing into compartments, groups of tubes within each of said compartments separated by lanes, and means for independently controlling the flow of fluid through said lanes in each of said compartments.

2. In combination, a casing, means dividing said casing into laterally adjoining compartments, groups of tubes disposed within each of said compartments, said groups being separated by lanes extending transversely through said compartments, and adjustable means for independently controlling the flow of steam through said lanes in each of said compartments.

3. In combination, a casing, partitions dividing said casing into segregated compartments, groups of tubes within each of said compartments separated by lanes, and adjustable dampers for independently controlling the flow of fluid through said lanes in each of said compartments.

4. In combination, a casing having a top inlet and a lower outlet, means dividing said casing into compartments independently communicable with said inlet, groups of tubes within each of said compartments separated by lanes communicating with said inlet, and adjustable means for independently controlling the flow of steam from said inlet to said lanes in each of said compartments.

5. In combination, a casing having an inlet communicable with all portions of the interior of said casing, partitions dividing said casing into compartments communicating directly with said inlet, groups of tubes spanning each of said compartments and

separated from each other by lanes communicating with said inlet, and movable means within said lanes for independently controlling the flow of steam through each of said compartments.

5 In testimony whereof, the signature of the inventor is affixed hereto.

IRVING H. REYNOLDS.
